UNITED STATES PATENT OFFICE.

WILLIAM D. EWART, OF CHICAGO, ILLINOIS.

DRIVE-CHAIN.

SPECIFICATION forming part of Letters Patent No. 240,819, dated May 3, 1881.

Application filed January 5, 1881. (No model.)

To all whom it may concern:

Be it known that I, WILLIAM DANA EWART, of Chicago, in the county of Cook and State of Illinois, have invented certain new and useful Improvements in Drive-Chains; and I do hereby declare that the following is a full and exact description of the invention, reference being had to the accompanying drawings, making part of this specification.

10 My invention relates more particularly to that kind of drive-chains which is composed of a series of bars running in the direction of the length of the chain, hinged together at or near their ends, and arranged alternately singly and in pairs.

15 Previous to my invention this kind of chains has been made sometimes with the articulations of such construction as not to permit any separation of the parts of the chain after its manufacture, except by changing the condition of the parts, and sometimes with devices for coupling the bars together of such construction that any two of the links might be readily detached and recoupled by simply turning the parts desired to be uncoupled (on their axes of articulation) out of their relative working positions; and in this kind of chains, made either detachable or non-detachable, it has been customary, prior to my invention, to have the articulations composed wholly of projections 20 on the several parts adapted to bear against and interlock with each other, and so form hinge-like joints between the parts; but in such prior chains the bars composing the double or hollow link have always been permanently fastened together by one or more cross-rivets, and when made detachable such chains necessarily had the bars composing the double or hollow links thinner throughout their width elsewhere than at the locality of the articulate projections. They had to have the parts turned very far back to effect an uncoupling, and the latter was effected by a peculiar movement of the single link (carrying the male members of the articulation) and without changing the relation of the bars composing the double or hollow link.

25 My invention has for its object to provide for use a detachable chain of the class referred to, in which there shall be no means of permanent securement of the bars com-

posing the double links, in which each of said bars may be flanged throughout its entire length to a thickness at its edges equal to the thickness at the locality of the articulate projections of said bars, and in which, when the parts shall have been turned into an unusual relative position, the uncoupling is effected by not only the detachment of a single link from a double one, but also by a separation of the bars composing the double link.

30 To these ends and objects, and also to provide a stronger and in other respects more desirable detachable chain of the class referred to than has heretofore been made, my invention consists in a drive-chain composed of alternately arranged single-bar and double-bar links, each single-bar link having laterally-projecting lugs, and the bars of the double links each having holes or receptacles adapted 35 to the reception and retention of said lugs, the whole being constructed and operating together, as will be presently more fully described, so that while in working positions the links (when coupled together) will be all hinged 40 or articulated, and when turned into an unusual relative position the links may be uncoupled by the separation of the bars of any double link from the adjacent end of two single links, and from each other by a lateral movement only of the parts.

45 My invention further consists in a detachable drive-chain composed of bars running in the direction of the length of the chain, and arranged alternately, singly and doubly, as set forth, having the articulations composed 50 of projections which bear against each other, and having the parts so articulated capable of separation, when turned out of the working position, by a relative movement laterally only 55 of the parts to be separated, all as will be hereinafter more fully explained.

55 To enable those skilled in the art to make and use my invention, I will now proceed to more fully describe it, referring by letters of 60 reference to the accompanying drawings, forming part of this specification, and in which I have illustrated my invention in that form, or have shown that mode of carrying out my invention which now appears to me to be the best, and in which I have successfully practiced it.

In the drawings, Figure 1 is an edge view; Fig. 2, a top or plan view; Fig. 3, a view illustrating the method of uncoupling the parts; Fig. 4, a vertical section at xx , Fig. 1; Fig. 5, a detail sectional view at line yy , Fig. 2; and Fig. 6 a detail view, showing a certain modification of form of some of the parts.

Wherever the same parts are visible in different figures they will be found designated by the same reference-letter.

The chain is composed of alternate single-bar links A and C, and double-bar links, each formed, as shown, of two similar bars, B B, each of which bars B is made, preferably, with flanged edges b , the semicircular and more adjacent surfaces of which flanges, on the inner sides of the bars B B, constitute, as shown, the female members, at opposite ends of the link, of the articulations of the chain. Near each end of each single-bar link, and on opposite sides of the bar, are circular disk-like projections e , which are adapted to bear and work against the said semicircular portions of the flanges b , and from each of these articulate projections e projects a cylindrical stud or pin, f , the end of which is formed or provided with a sort of cross-head, i , thus giving the device $f i$ a construction and appearance analogous to that of a T-bolt. (See Fig. 4.)

In each of the bars B B of the double link are holes or receptacles s , for the accommodation of the studs f , with their heads i , in a manner and for purposes to be presently explained; and the arrangement of the oblong holes s and heads i of the double and single bar links respectively is such, as shown, that when the links of the chain are in line, as seen in Figs. 1 and 2, the heads i will stand crosswise of the direction of length of the holes s .

When the parts alluded to are all together and the chain in a working condition, as seen at Figs. 1, 2, and 4, the articulations, it will be understood, are composed essentially of the disk-like projections e and the semicircular flange-like surfaces b , against which said disks e bear and work during the operations and draft of the chain, and the studs f , though engaged with and turning within the central enlarged portions of holes s , do not fit any portions of said holes snugly enough to come to a frictional bearing therein during the draft of the chain, but operate merely to prevent any material backing out of the disks e from their opposing female bearing-surfaces when the chain is not under tensional strain, while the cross-heads i operate (in an obvious manner) to prevent any lateral displacement of the parts of the chain.

Whenever it may be desired to uncouple any of the parts of the chain, this end may be accomplished by turning the parts to be detached into the relative position illustrated by Fig. 3, where, also, is illustrated the removal of one of the bars B from the two single links A and C. Of course the other bar B may in

like manner be removed, and any number of pairs of parts may be subtracted from or added to the chain to shorten or lengthen it. The relative position of the parts necessary to thus permit their detachment is one which they cannot assume while the chain is in operative use, and hence there is no liability of any uncoupling of the chain parts, except by design.

The partial section at Fig. 5 illustrates most clearly how the bars B may be easily detached from the single-bar links when the parts shall have been turned in the positions seen at that figure and at Fig. 3, while an observation of the other figures shows how the coupling devices are inseparable when the chain is in its working condition.

It will be understood that the bars B might be made with properly-shaped concavities cast in them at the vicinities of and instead of the holes s , so that the cross-heads i and studs f might engage with such concavities and not pass through the stock of the bars B, and that many other variations of form and details might be made without materially changing either the principle of construction or mode of operation of the improved chain shown and described; also, that the projections e and flanges b might be transposed in their respective relations to the single-bar and double-bar links, and that a portion only of my invention may be used with great advantage. For instance, if the male projections e of the articulations should be entirely omitted, either with or without the omission also of the flanges b , the studs f and the receptacles in which they work would then constitute the articulations, and the parts of the chain could be separated only when turned into the positions already explained as necessary for uncoupling. In such case, however, it would be preferable to make the heads of studs f project only at one side, and the holes s of the shape shown at Fig. 6, in order that during the working-strain there would be afforded a sufficient bearing-surface between the bearing-surface of stud f and the semicircular portion of hole s , and to increase this bearing-surface the size of the stud and hole s might be increased.

I do not wish it to be understood that my invention is necessarily restricted to the employment at once of all the features of invention which I have herein described and shown; but—

Having so fully shown and described a chain embracing all the separable features of my invention that any one skilled in the art can practice the said features of my invention either together or separately, what I claim as new, and desire to secure by Letters Patent, is—

1. A drive-chain composed of alternately-arranged single-bar and double-bar links provided respectively with projecting lugs and holes, substantially as set forth, and adapted to be uncoupled and recoupled when the parts are turned into an unusual relative position,

as set forth, by a lateral movement only of the parts relatively, as hereinbefore described.

2. A drive-chain composed of alternate single and double bar links, the articulations of which are composed, essentially, of male and female projections, constructed substantially as described, adapted to bear against each other, and to be coupled or uncoupled when the links

are turned out of a working position by a lateral movement only of the parts relatively.

In witness whereof I have hereunto set my hand this 28th day of October, 1880.

WILLIAM D. EWART.

In presence of—

S. HOWARD SMITH,
C. R. MATSON.
